UNITED STATES PATENT OFFICE.

EDWIN HARTZELL, OF WILKES-BARRE, PENNSYLVANIA, ASSIGNOR OF
ONE-HALF TO JOHN P. BENNING, OF WILKES-BARRE, PENNSYLVANIA.

SIFTER, SEPARATOR, AND GRADER.

No. 824,650.

Specification of Letters Patent.

Patented June 26, 1906.

Application filed February 18, 1905. Serial No. 246,282.

To all whom it may concern:

Be it known that I, EDWIN HARTZELL, a citizen of the United States, residing at Wilkes-Barre, in the county of Luzerne and State of Pennsylvania, have invented a new and useful Improvement in Sifters, Separators, and Graders, of which the following is a specification.

This invention relates to a device for sifting, separating, and grading grains, coffee, spices, and similar light articles of merchandise.

The object of the invention is a device which will perform the above-mentioned functions with one running of the material through the device and without a multiplicity of shakers or complicated gearing.

The invention consists in the novel arrangement of the sieves and boxes, the novel manner of rocking the boxes from a common rock-shaft, and in subjecting the graded and sifted material to the action of a suction-fan adjacent the point of discharge for the purpose of removing such parts as chaff, hulls, and the like.

The invention further consists in the novel features of construction hereinafter described, pointed out in the claims, and shown in the accompanying drawings, in which—

Figure 1 is a perspective view of the machine. Fig. 2 is a vertical longitudinal section. Fig. 3 is a section on the line 3 3 of Fig. 2. Fig. 4 is a view looking toward the discharge end of the device. Fig. 5 is a detail sectional view taken on the line 5 5 of Fig. 2. Fig. 6 is a detail perspective view showing an end of a rocker-arm and one face of the connecting-plate.

In constructing my device I employ a frame A, in which is pivotally suspended divergently-arranged boxes B and C in vertical alinement. These boxes are suspended by hanger-rods D, pivotally connected to cross members of the frame A at their upper ends and to the sides of the boxes at their lower ends, whereby the boxes are free to swing longitudinally. The box B carries a screen placed a short distance above the bottom of the box, the said bottom being preferably of galvanized iron, and at its lower end the box B is provided with an outlet or discharge slot B². The slot B² is above the lower end of the screen B', and in the bottom of the box, adjacent its lower end, is an opening B³. Downwardly-extending discharge-chutes are ar-

ranged below the lower end of the box B, one of which, G, receives the material discharged through the opening B³ and conveys it to the exterior of the frame, discharging it to one side. The other chute H receives the material discharged from the slot B² and conveys it to the upper end of the box C. In the box C are placed two screens J and J', the screen J being the coarser and both being of coarser mesh than the screen B', which is the finest-mesh screen employed. I prefer to construct these screens of sheet metal with apertures punched therein.

Between the divergent ends of the boxes B and C, I place a fan-casing E, opening to the rear of the frame A, and in which I place a fan E', mounted on a shaft E², which at one end carries a pulley E³. Above the upper end of the box B, I place a feed-hopper F, which contains a valve F', to which is connected a lever F² or scale-beam, on which is placed an adjustable weight F³. The weight and valve regulate the feed of material to the box B and insure an even flow of the material, the amount to be fed being regulated by adjusting the weight along the lever F².

Two wind-trunks K and K' lead to the fan-casing, the trunks joining above the lower end of the box C. A valve K² is placed at the juncture of the two trunks and can be shifted so that both trunks can be used or can be partially rotated to close either of them. The trunk K has a lower detached section K³, which is carried by the shaking-screen C, as shown in Fig. 2. A deflector-plate L is placed in the lower end of the trunk K' adjacent the lower end of the box C. Discharge-chutes M lead from the box C above the screen J to the exterior of the frame, one chute M discharging on one side of the device and the other upon the opposite side. The box C is provided with openings C' and C², corresponding, respectively, to the openings B² and B³, the opening C' giving communication to the trunk K', which in turn opens downwardly into a receptacle O. The opening C² opens downwardly into a receptacle O'.

To operate the device, a shaft P is journaled in the frame on which is fixed an eccentric P', and to the eccentric-strap is secured a rod P², which is pivoted to a rocker-arm R, carried by a rock-shaft R'. The rock-shaft R' carries adjacent its ends upwardly and down-

wardly extending arms S. The upper and lower ends of the arms S are slightly offset and are slotted, as shown in Fig 6. Plates S' are connected to the sides of the boxes and 5 carry pins S², adapted to engage the slots of the arms. The upper ends of the arms connect with the plates S', carried by the box B, and the lower ends of the arms with the plates S', secured on the sides of the box C. 10 A pulley P³ is carried by one end of the shaft P, and a belt runs over the pulley P³ and the pulley E³. On the opposite end of the shaft P is secured a drive-pulley P⁴.

In operation the finest of the material 15 passes through the screen B' and is discharged to one side of the device through the chute G. The remainder of the material passes down the chute H into the box C, and the coarsest of the material fails to pass 20 through the screen J and is delivered to the side of the machine through the chutes M. A portion of the material will pass through the screen J, but not through the screen J', and this material will be delivered to the box 25 O and will also be subject to the suction of the air-current in the trunks K and K', and any light articles—such as hulls, chaff, &c.—will be drawn upwardly and discharged to the rear of the fan-casing E, the remainder 30 passing into the box O. The finest material, which passes into the chute H, will pass through both screens J and J' and will be discharged into the box O'. Both boxes B and C will be rocked by the arms S, the boxes 35 rocking in opposite directions without undue vibrations of the frame A. The various screens are removable, either for purposes of cleaning or for varying the size of mesh to be employed. In order that the draft may be 40 regulated for work with various materials, I provide a supplemental draft-opening E⁴, provided with a slide E⁵, so that the amount of air supplied to the fan-casing E can be regulated to suit the requirements, and it is 45 also obvious that both or either one of the wind-trunks can be used by adjusting the valve K², the valve being set by the lever K⁴. (Shown in Fig. 1.)

Having thus fully described my invention, 50 what I claim as new, and desire to secure by Letters Patent, is—

1. A device of the kind described comprising downwardly and oppositely inclined boxes, a sieve in the upper box, a double 55 sieve in the lower box, the said sieves in the lower box being arranged one above the other and the upper one terminating at its

lower end short of the lower one, a discharge chute between the two boxes, common means for rocking both boxes, a receptacle 60 adapted to receive material passing through the lower sieve of the lower box, a receptacle receiving material from the said lower sieve, a fan-casing, a fan therein, a wind-trunk leading to said fan-casing and communicating at its lower end with the lower box adjacent 65 the end of the upper sieve, and a second wind-trunk leading to the fan-casing and communicating at its lower end with the last-mentioned receptacle. 70

2. A device of the kind described comprising upper and lower oppositely - inclined boxes, means for oppositely rocking the boxes, a sieve in the upper box, a plurality of sieves in the lower box, discharge-chutes 75 alining with the lower end of the upper box, one of said chutes discharging into the upper end of the lower box, the said lower box having openings at its lower end respectively above and below the bottom sieve, receptacles alining with said opening, discharge-chutes leading from the lower box adjacent its lower end from a point above the top sieve, wind-trunks extending upwardly respectively from the lower end portion of the 85 lower box and from adjacent the said end, and means for creating an upward current of air through the said trunks. 80

3. A device of the kind described comprising suspended boxes in vertical alinement, a discharge-chute between the boxes, sieves arranged longitudinally in the lower box and one above the other, said sieves being of different mesh, discharge-chutes arranged at the lower end of the said box adapted to convey material from the box from a point above the top sieve, the said box having an opening at the end adapted to discharge material from between the sieves, and an opening in the bottom, receptacles alining with said 95 openings, a wind-trunk having valve-controlled branches one branch opening downwardly into the lower end of the said box above the top screen and the other branch having communication with the opening in 100 the end of the box, a deflector - plate adjacent said end opening, and means for creating and maintaining a current of air upwardly through said trunks. 105
